UNITED STATES PATENT OFFICE.

LOUIS GOLDSTEIN, OF BROOKLYN, NEW YORK.

TURNOVER MACHINE.

Application filed February 17, 1923. Serial No. 619,723.

To all whom it may concern:

Be it known that I, LOUIS GOLDSTEIN, a citizen of the United States, and a resident of the city of New York, borough of Brooklyn, in the county of Kings and State of New York, have invented a new and Improved Turnover Machine, of which the following is a full, clear, and exact description.

This invention has relation to a turnover machine, the same being in the nature of an improvement over a prior patent granted to me June 14, 1921, and bearing United States Letters Patent No. 1,381,820.

The invention contemplates as its main object the provision of an apparatus for the facilitating of the turning over or inverting of tubular articles or structures such as fabric belts or the like by means of which the inverting or turnover process may be rapidly accomplished without danger of injuring the article and without requiring the services of a skilled operator.

As a further object the invention provides in an apparatus or machine of the character described means for adjusting the gripping elements whereby their relative spacing when in gripping position may be varied to render the device useful in connection with articles or structures of various thicknesses.

As a still further object the invention contemplates a machine or apparatus of the character described which is extremely simple in its construction, inexpensive to manufacture and which is thoroughly reliable and highly efficient in its purpose.

With the above recited and other objects in view the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a plan view of a machine or apparatus constructed in accordance with the invention.

Fig. 2 is an enlarged detail sectional view taken approximately on the line 2—2 of Fig. 3.

Fig. 3 is a longitudinal sectional view

taken approximately on the line 3—3 of Fig. 2.

Fig. 4 is a detail fragmentary perspective view of the outer end of the spindle.

Referring to the drawings by characters of reference, the invention in its broad interpretation consists of a spindle which includes an outer tubular member 10 and an inner member 11 axially movable through the outer member. At one extremity the inner member is provided with a head 12 formed at its juncture with the member 11, with a flared or frusto-conical portion 13. At the corresponding end of the outer member 10 a complementary flared or frusto-conical seat 14 is provided which is formed with a notch 15 communicating therewith for a purpose to be hereafter set forth. At the opposite end the inner member 11 protrudes beyond the end of the outer member 10 whereby the operator upon axial movement of the member 11 in one direction may draw the frusto-conical or flared portion 13 of the head 12 against the seat 14 of the outer member 10 and upon the movement in the opposite direction effect relative separation between the faces 13 and 14.

In use and operation of the device the tubular structure A which may have either an open or closed end B is drawn onto the spindle. Where the end B is closed it is, of course, understood that the headed end 12 of the inner member 11 is arranged at the closed end B. Where both ends of the structure A are open it is immaterial which end is arranged adjacent the headed end 12 of the member 11. Assuming that the structure A is provided with a closed end B as illustrated, the operator with the faces 13 and 14 separated, draws the closed end B in between the two faces 13 and 14 allowing a portion of the material to lie in the notch 15; the members 10 and 11 are then moved axially with respect to each other to advance the faces 13 and 14 toward each other whereby a portion of the end B of the structure A is gripped between said faces. The turning over or inverting operation is then accomplished by grasping the structure A adjacent the gripped end and pushing the same outward over said gripped end as illustrated in Fig. 3 of the drawings.

In order to provide means for accomplishing the axial relative movement between the members 10 and 11 and for lock-

ing the same to hold the gripping faces 13 and 14 in gripping position with the structure A, a manipulating mechanism is provided which consists of a stationary supporting bracket 16 having an aperture 17 in which the inner end of the outer member 10 of the spindle is positioned and retained by means of set screws 18. The bracket 16 is preferably formed into a U-shaped clamp 19, one arm or side 20 of which is adapted to rest upon a table or bench C, the opposite arm or side 21 of which is designed to underlie in spaced relation the table or bench C. The arm 21 is provided with a threaded aperture 22 through which a threaded shank 23 extends the same being provided with a swiveled head 24 at its upper end and a manipulating handle 25 at its opposite end. This arrangement permits of a detachable rigid association of the bracket 16 and the spindle with a table, bench or other support whereby the spindle will be rigidly maintained in a spaced parallel position above the table. The end opposite from the headed end 12 of the member 11 which will be hereinafter termed the "inner end" and which projects beyond the inner end of the outer member 10 is threaded as at 26 and extends loosely into the axial bore 27 of one end of an operating rod 28. The opposite reduced end 29 of the bar 28 is mounted for sliding movement in a cup shaped bearing 30. The bearing 30 has its cylindrical portion 31 received in an apertured lug 32 provided on the bracket 16. The head portion 33 of the bearing 30 is of larger diameter than the cylindrical portion 31 and provides a peripheral bead or flange 34 which acts as a stop for preventing inward movement of the bearing member in the lug 32. The head 33 is centrally apertured as at 35 to snugly receive the reduced end 29 of the operating rod 28 which extends therethrough and is pivoted as at 36 to an eccentric handle 37, said handle 37 having bearing rollers 38 journaled therin for engagement with the headed portion 33 of the bearing member 30. The medial portion of the operating rod 28 is exteriorly threaded as at 39 and has threadedly engaged thereon an adjustable abutment nut 40 and a binding nut 41. A coiled expansion spring 42 surrounds the operating rod 28 and is interposed between the adjustable abutment nut 40 and the inner side of the head 33. The operating rod 28 forms a boss or extension from a slide block 45 which is suitably maintained against turning movement. The slide block is provided with apertured knuckles 46 and 47, the apertures of which are in axial alignment with the bore 27 of the operating rod. The threaded end 26 of the member 11 extends through the knuckles 46 and 47 and a rotary knurled adjusting nut 48 is interposed between the knuckles 46 and 47.

and threaded to the end 26 for connecting the member 11 with the slide block and operating rod 28 for movements therewith. By this arrangement it will be understood that by turning the adjusting nut 48 an initial relative spacing between the gripping faces 13 and 14 may be obtained to adapt the machine or device to tubular structures A of various thicknesses. A binding nut 49 is also threaded onto the threaded end 26 of the member 11 to bear against the outer side of the knuckle 47 whereby when the adjusting nut 48 has been properly manipulated the binding nut 49 will prevent accidental movement of the same.

In practice and where found desirable, a plurality of spindles of various diameters may be used and connected with a common bracket 16 in which instance the spindles are disposed in parallel relation with the slide blocks 45 of each pair of spindles having a tongue and groove connection 50 and 51 which serves to permit of relative sliding movement of the blocks while at the same time preventing turning movement thereon. In this instance the spindles are provided with independently operable manipulating mechanisms.

From the foregoing the operation is as follows: The operator after placing the tubular structure A over the end of the spindle with the eccentric handle 37 in an upright position to space the gripping faces 13 and 14 apart draws the outer end of the tubular structure about the end of the spindle to dispose a portion between the gripping faces. The operator then grasps and turns the eccentric handle 37 to a horizontal position thereby effecting relative axial movement between the inner member 11 and outer member 10 to advance the head 12 toward the outer end of the outer member 10 to cause the gripping faces 13 and 14 to tightly grip the tubular structure A. Due to the fact that the bearing rollers 38 have a past center movement the members 10 and 11 will be retarded against the further movement and the gripping faces locked in gripping position. The operator then proceeds to grasp the tubular structure A at a point inward from the end of the spindle and pulls downwardly thereon to effect the inverting or turning over of the structure. When the inner end of the structure has passed over the outer end of the spindle and the gripped extremity of the structure, the handle 37 is swung upwardly to release the gripping faces.

It will thus be seen that an improved form of turnover apparatus or machine is provided which greatly facilitates the turning over operation of any tubular flexible structure which it is desired to invert.

I claim:

1. An apparatus for inverting flexible

- tubular structures, comprising a spindle including inner and outer axially movable members respectively provided with complementary gripping faces at the adjacent ends 5 of the members, means at the opposite end of the spindle for effecting relative axial movements of said members and for retaining the same in their relatively axially moved positions, and an adjustable means of connection 10 between said means and the inner spindle member for regulating the spacing between the gripping faces when in gripped position to compensate for various thicknesses in the flexible structure to be inverted.
- 15 2. In an apparatus for inverting flexible tubular structures, a spindle comprising an outer tubular stationary member having a flared conical seat at its outer end, an inner member axially movable through the outer member, a conical head at the outer end of said inner member, said conical head and seat constituting complementary gripping faces between which the outer end of the tubular structure is adapted to be gripped, 20 manipulating means connected with the inner end of the inner spindle member for axially moving and retaining said inner member and its head respectively toward and away from the conical seat of the outer spindle member, and the connection between 25 the manipulating means and the inner end of the inner spindle member being adjustable for regulating the space between the conical head and conical seat when moved to gripping position to compensate for variation 30 in the thickness of the structures gripped thereby.
3. In an apparatus for inverting flexible tubular structures, a spindle over which 35 the structure is arranged comprising inner and outer telescopic members formed with complementary gripping faces at the outer end for gripping one end of the structure, and a combined manipulating and retaining means at the opposite end of the spindle for effecting relative axial movements of the inner spindle member with respect to the outer spindle member, said manipulating means comprising a supporting bracket to which the inner end of the outer member is rigidly attached, a pivoted eccentric handle with which the inner end of the inner member is connected, and means for maintaining said eccentric handle 40 respectively in its positions to dispose the gripping faces in open or closed relation.
4. In an apparatus for inverting flexible tubular structures, a spindle over which the structure is arranged comprising inner and outer telescopic members formed with complementary gripping faces at the outer end for gripping one end of the structure, and a combined manipulating and retaining means at the opposite end of the spindle for effecting relative axial movements of the inner spindle member with respect to the outer spindle member, said manipulating means comprising a supporting bracket to which the inner end of the outer member is rigidly attached, a pivoted eccentric handle with which the inner end of the inner member is connected, and means for maintaining said eccentric handle 45 respectively in its positions to dispose the gripping faces in open or closed relation.
5. In an apparatus for inverting flexible tubular structures, a spindle over which the structure is arranged comprising inner and outer telescopic members formed with complementary gripping faces at the outer end for gripping one end of the structure, and a combined manipulating and retaining means at the opposite end of the spindle for effecting relative axial movements of the inner spindle member with respect to the outer spindle member, said manipulating means comprising a supporting bracket to which the inner end of the outer member is rigidly attached, a pivoted eccentric handle with which the inner end of the inner member is connected, and means for maintaining said eccentric handle 50 respectively in its positions to dispose the gripping faces in open or closed relation.
6. An apparatus of the character set forth comprising a bracket having means for clamping the same to a support, a spindle projecting from said bracket comprising an outer tubular member rigidly connected to the bracket and the inner member axially movable through said outer member, complementary gripping faces formed at the outer ends of said members, an eccentric handle mounted on said bracket, and an adjustable connection between said handle and the inner end of the inner member for respectively advancing the gripping face of the inner member toward and away 55 from the gripping face of the outer member upon manipulation of the handle.

LOUIS GOLDSTEIN.
